UNITED STATES PATENT OFFICE.

HOWARD T. SIMONS, OF CAMBRIDGE, OHIO.

SLEIGH-BELL FASTENER.

SPECIFICATION forming part of Letters Patent No. 364,311, dated June 7, 1887.

Application filed September 10, 1886. Serial No. 213,232. (No model.)

To all whom it may concern:

Be it known that I, HOWARD T. SIMONS, a citizen of the United States, and a resident of Cambridge, in the county of Guernsey and State of Ohio, have invented certain new and useful Improvements in Sleigh-Bell Fasteners; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of one form of my improved fastener. Fig. 2 is a similar view of another form. Fig. 3 is a longitudinal median section of a portion of a "string of bells," illustrating my fasteners applied. Fig. 4 is a perspective view of a narrow metal-faced strap with a bell secured thereto with the improved fastener, and Fig. 5 is a vertical sectional view showing another manner of securing a bell to the fastener.

Like letters of reference indicate corresponding parts throughout the several figures.

My invention has relation to sleigh-bell fasteners and to certain improvements in sleigh-bell straps; and it consists in the improved construction and combination of parts, as will be hereinafter fully set forth.

The object of my invention is to provide a fastener to which sleigh-bells may be readily riveted or screwed, and which can be easily and securely attached to plain straps or metal-faced straps without perforating said straps with holes larger than those ordinarily made for buckle-tongues, thus avoiding the necessity of cutting a large hole in the strap, as is required in attaching the old style of bell with its wide lug and wire key, which key, wearing upon the spot weakened by the hole for the lug, soon severs the strap. Furthermore, this improved fastening is intended to dispense with the extra strap or inside lining generally used to cover the old fasteners, thus discarding the leather loops employed in securing said lining to the bell-strap.

Another object accomplished by this invention is, that the bell-strap can be made narrower than formerly, thus rendering it less ex-

pensive to face the strap with thin sheet metal, which, while ornamenting the "string," also adds strength.

In the accompanying drawings, A represents the parallel arched end pieces of the metallic frame which constitutes the fastener; B, the side pieces which join the opposite ends of the end pieces, and C the middle piece joining the summits of the arched end pieces. From said middle piece upwardly projects a stud, D, which serves as a securer for a bell, E. The bell has a boss formed upon its lower side, through which into the bell is formed a smooth or screw-threaded perforation, allowing the bell to be riveted or screwed to the fastener, as seen in Fig. 3; or the bell may be provided with a lug upon its lower side, which may be screwed or riveted into a perforation formed in the center of the middle piece of said frame, as seen in Fig. 5.

One form of fastener has a single tongue, F, downwardly projecting from the center of the middle piece, and the other has a similar tongue, G, upwardly projecting from the center of each of the side pieces. These tongues serve in securing the fasteners to the strap I, which is passed over the side pieces and under the middle pieces, the tongues entering the holes formed for them.

The bell and fastener may be cast together, if desired, though, in point of economy, it is preferable to cast the fastener from malleable iron or some other metal which is not so expensive as bell-metal.

The sheet-metal facing-strip J may be secured to the strap in any ordinary manner, or simply by the bell-fasteners, and may be made from any body metal plated with any of the nobler ones.

Having thus fully described my invention, I claim—

1. A sleigh-bell fastener consisting of a frame formed with arched end pieces, side pieces joining said end pieces and each having a stud upwardly projecting from its middle, and a middle piece furnished with means for attaching a bell thereto.

2. The combination, with a sleigh-bell provided with a bossed perforation on one side, of a fastener consisting of a frame for attach-

ment to a strap, provided with an upwardly-projecting stud adapted to be secured in said perforation.

3. The combination of a sleigh-bell provided with a lug upon its lower side and a frame adapted to be attached to a strap, and provided with an aperture in the center of the middle piece of said frame to receive said lug.

4. The combination, with a metal-faced strap, of a sleigh-bell connected to a fastener consisting of a frame formed with arched end

pieces, side pieces, and a middle piece, from the under side of which centrally projects a tongue for securing said fastener to said strap.

In testimony that I claim the foregoing as my own I have hereunto affixed my signature in presence of two witnesses.

HOWARD T. SIMONS.
